CLAIM

The ornamental design for pants with condom pocket, as shown and described.

DESCRIPTION

FIG. 1 is a front perspective view of pants with condom pocket showing my new design;

FIG. 2 is a front perspective view from the left thereof;

FIG. 3 is a left perspective view thereof;

FIG. 4 is a rear perspective view thereof, wherein the lower obscured portion of the pocket is a mirror image of the top visible portion; and,

FIG. 5 is a top perspective view thereof.

The broken line showing of pants and of round patch on the condom pocket is for illustrative purposes only and forms no part of the claimed design.

Surface shading on FIG. 1 and FIG. 2, is provided merely to highlight the contour of design; it is not intended to be illustrative of texture or gloss.
